UNITED STATES PATENT OFFICE.

NEM WILLIAM BRANNON, OF GREER, SOUTH CAROLINA, ASSIGNOR TO DRAPER CORPORATION, OF HOPEDALE, MASSACHUSETTS, A CORPORATION OF MAINE.

INTERMITTENT THREAD-CUTTING TEMPLE.

Application filed April 7, 1926. Serial No. 100,315.

This invention relates to a thread or filling cutting temple for looms of the automatic filling replenishing type.

The object of the invention is to provide such a temple in which the cutting mechanism shall be operative only immediately after the operation of the filling replenishing mechanism and only until the filling end left by the discharged filling carrier is cut 10 thereby.

The object of the invention is therefore to relieve wear and tear on the cutting mechanism, to eliminate the continual operation of the cutting mechanism, and consequently 15 to provide a cutting mechanism of an improved and efficient intermittently operating type.

As is well known to those skilled in the art, the purpose of the cutting mechanism 20 connected with the temple is to cut off close to the selvage the filling ends left after replenishment of the filling. Notwithstanding the fact that replenishment of filling only takes place occasionally during the operation of the loom, it is the general practice for the cutting mechanism to be operated 25 at each beat-up of the lay. The present invention provides for an intermittent operation of the cutting mechanism under the control of the filling end left by the discharged filling carrier and thus insures that the operation shall take place only at the required time and only for a sufficient period to enable it to perform its function.

These and other objects and features of the invention will appear more fully from the accompanying description and drawings and will be particularly pointed out in the claims.

As the general operation and construction of the automatic filling replenishing loom and of the thread cutting temple are well known and familiar to those skilled in the art, it is only necessary to illustrate and describe in detail those parts directly concerned with the present invention.

The drawings therefore illustrate only so much of a filling replenishing loom of the well-known Northrop type as is sufficient to disclose the preferred form of the present invention.

In the drawings:

Fig. 1 is a plan view of a portion of the loom with a temple embodying a preferred form of the invention and with the parts

in the position assumed immediately after replenishment has taken place.

Fig. 2 is an elevation of the temple and thread cutting mechanism shown in Fig. 1 looking toward the front of the loom. 60

Fig. 3 is a side elevation of the mechanism shown in Fig. 2 with the cutting mechanism in inoperative position.

Fig. 4 is a view similar to Fig. 3 with the cutting mechanism in operative position. 65

The loom, a portion of which is illustrated, comprises the lay 1 having the shuttle box 2 which swings toward and from the breast beam 3. On the breast beam at the replenishing side is mounted the usual magazine or 70 hopper 4 carrying the supply of fresh filling carriers, one of which at the time of replenishment is forced into the shuttle box on the lay discharging therefrom at the same time the exhausted or substantially exhausted filling carrier. 75

The loom is shown as provided with a shuttle feeler 5 of a familiar type which, by usual mechanism unnecessary here to illustrate, is moved rearwardly across the path of the shuttle and then forwardly to its normal position illustrated in Fig. 1. This shuttle feeler is shown as provided with the usual filling parting and clamping mechanism 6 which clamps and parts the filling end 7 extending from the cloth to the discharged filling carrier at the time of replenishment and carries this clamped filling end forward and holds it until it is severed by the temple thread cutter. 80

The temple is also of any suitable familiar type and comprises a head portion 8 having a shank 9 mounted to reciprocate in a stand 10 supported from the breast beam of the loom, all in a familiar manner. 85

The thread or filling cutting mechanism may be of any suitable type such, for example, as that shown in the patent to Draper et al, No. 585,465, granted June 29, 1897. 100 As illustrated, this mechanism is mounted in the temple head 8 through which extends forwardly and rearwardly a slot 11. At the rearward end of the slot a fixed cutter blade 12 is mounted. A movable cutter member 13 is mounted to rock and slide forwardly and rearwardly in the slot 11 and is provided at its rearward end with a pair of hook-shaped cutter blades 14 straddling and cooperating with the fixed blade 12. This movable cutter member is projected rear- 105 110

wardly by the usual spring 15 having an eye at its lower end engaging a laterally projecting stud 16 on the cutter member and having an eye at its upper end engaging a laterally projecting stud 17 on the temple head, the extreme upper end of the spring resting against a shoulder 18 on the temple head. The cutter member is moved forwardly to effect the cutting operation by the lay striking against a depending heel 19.

In a preferred form of construction embodying this invention, the required mechanism is mounted on the temple by means of a bracket 20 secured to the temple shank 9 by means of a bolt 22, while the bracket 20 itself rests upon the top of the temple head. This bracket 20 is bent near its middle portion at 23 to form a bearing and again at its free end at 24 to form a second bearing, in which bearings is journalled or pivoted a shaft 25 constituting a part of a latch. This latch is provided at the temple end with a locking arm 26 and at the opposite end with a bunter arm 27. The locking arm 26 is conveniently formed by bending the shaft 25 downwardly and laterally. The lateral portion of this locking arm 26 is so arranged as to swing down behind a rearwardly facing vertical shoulder 28 formed at the forward end of the movable cutter member 13. When the locking arm is swung to this position, as shown in Fig. 3, it stands between the forward edge of the head of the temple and the shoulder 28 of the movable cutter member and holds the movable cutter member nearly at its extreme forward position and in an inoperative position or a position where it cannot catch and cut the filling. In this position the rear face of the heel 19 is slightly in front of the rear face of the usual depending heel 29 of the temple itself. It will thus be seen that as the lay strikes the heel 19 and moves it forward until the lay comes into engagement with the heel 29, there will be a slight forward movement of the movable cutter member which will free the locking arm 26 and enable it easily to be swung out from behind the shoulder 28.

The bunter arm 27 is shown as a wire member adjustably clamped by means of a screw 30 between a base block 31 and a cap block 32, the former of which is rigidly secured in any suitable manner to the shaft 25. The shank 33 is extended forwardly beyond the base and cap blocks, bent downwardly and back parallel with itself to form a loop 34 and then back between the base and cap blocks at 35. A counterbalancing weight in the form of washers 36, the number, size and weight of which may be varied as desired, is adjustable toward and from the piv-

tal axis of the latch shaft 25, or generally radially thereof, by means of a bolt 37 which locks the washers to the loop 34 in any desired position.

The counterbalancing weight is so proportioned and adjusted that the latch as a whole, comprising the bunter arm, shaft 25, locking arm 26, blocks 31 and 32, and the counterbalancing weight itself, will cause the locking arm normally to swing downwardly or into the position shown in Fig. 3, while at the same time a very slight pressure against the bunter arm 27 will enable the latch to be rocked in the opposite direction to release the movable cutter member.

The bunter arm 27, when the latch is in normal locking position with the movable cutter member held in a forward inoperative position, stands vertically about midway between the shuttle feeler and the temple head and parallel with, and preferably slightly forwardly of, the rear face of the temple head, as shown in Fig. 3. In this position the cutting mechanism is inoperative and the movable cutter member is subject only to a very slight movement upon the beat-up of the lay.

When now filling replenishment takes place, the shuttle feeler 5 is swung rearwardly and the clamping and parting mechanism 6 connected therewith clamps and parts the filling end 7 extending from the fell to the discharged filling carrier and then swings forwardly carrying the filling end with it. During this movement the filling 7 is carried into the usual notch 38, which positions it in the field of the cutting mechanism, and then forwardly against the bunter arm 27 producing a substantial amount of pressure on the bunter arm. When now the lay beats up, it presses the heel 19 forwardly slightly and at once the pressure exerted by the filling on the bunter arm 27 rocks the latch on its pivotal shaft 25, raising the locking arm 26 out from behind the shoulder 28 of the movable cutter member and releasing the cutter member which, as the lay retracts, is thereupon projected rearwardly by the spring 15. Upon the next beat-up of the lay, the movable cutter member 13 is actuated in the usual manner to cut the filling 7, and any other filling end projecting from the fell, close to the selvage. If the filling end 7 is not cut at the next beat-up, the movable cutter member continues to operate, the latch being held in unlocked position by the continued pressure of the filling 7 on the bunter arm 27, until the filling is cut. As soon as the filling is cut, the pressure on the bunter arm 27 is removed and the latch under the influence of the counterweight rocks to swing the locking arm 26 downwardly and as the movable cutter member is carried to its extreme forward position by the lay, the locking arm again drops behind the

shoulder 28, placing the movable cutter member again in inoperative position.

The mounting of the shank of the bunter arm 27 between the blocks 31 and 32 enables 5 the bunter arm 27 to be adjusted accurately in the required position so that the right amount of pressure against the bunter arm will be produced by the filling when carried forwardly by the shuttle feeler.

10 It will thus be seen that the cutting mechanism normally stands in an inoperative position subject to a minimum amount of wear and is only placed in operative position and only operates to sever the filling when replenishment actually takes place and that it only continues to function and remain in operative position until the filling is severed. Thus it is in operation only to the extent 15 and during the period actually required for 20 the cutting operation.

A mechanism embodying the invention may be readily attached to existing thread cutting temples when constructed in a manner such as herein disclosed because it is only 25 necessary to form the shoulder 28 in the usual movable thread cutter member and attach the necessary latch mechanism by means of a suitable bracket to the temple head and shank.

30 Having thus described the invention, what is claimed as new, and desired to be secured by Letters Patent, is:

1. In a loom a temple provided with filling cutting means, a latch normally movable into position to hold said cutting means in inoperative position, and a forwardly and rearwardly movable shuttle feeler provided with filling clamping means acting when it moves to, and remains in, forward position 35 40 with a clamped filling end to carry said filling against the latch and thereby to move the latch, when the latch is free to move, into, and hold it in, unlocking position and thus release the cutting means to operating 45 position and allow the said means to operate until it cuts the said filling.

2. In a loom a temple provided with filling cutting means including a cutter member movable rearwardly by a spring and forwardly by the lay, a latch normally movable 50 into position to hold said cutter member in a forward inoperative position, and a forwardly and rearwardly movable shuttle feeler provided with filling clamping means acting when it moves to, and remains in, forward position with a clamped filling end to carry said filling against the latch and thereby to move the latch, when the latch is free due to a forward movement of the cutter 55

member, into, and hold it in, unlocking position and thus release the cutter member and allow it to be operated until it cuts the said filling.

3. In a loom a temple provided with filling cutting means including a cutter member movable rearwardly by a spring and forwardly by the lay, a movable shuttle feeler provided with filling clamping means, and a latch in the form of a rock shaft having a bunter arm and a locking arm and balanced 60 65 to turn normally into a position to cause the locking arm to engage and lock the cutter arm in a forward inoperative position with the bunter arm standing in the path of the filling when carried forwardly by the shuttle feeler, whereby, when the lay beats up and moves the cutter member to extreme forward position and a clamped filling end is carried forwardly and held against the bunter arm by the shuttle feeler, the rock shaft 70 75 80 will be rocked to release the cutter member and will be held in released position until the filling is severed by the cutting means.

4. In a loom a temple, a movable cutter member mounted to slide forwardly and rearwardly in the temple and provided with a rearwardly facing vertical shoulder and a depending heel in the path of the lay, a forwardly and rearwardly movable shuttle feeler provided with filling clamping means, and a latch pivoted on the temple and provided with a locking arm and a bunter arm, the said latch normally rocking into position to cause the locking arm to drop behind the shoulder of the cutter member when in a forward position and thus maintain the cutter member inoperative, and the said bunter arm at all times standing in the path of a filling end when carried forwardly by the shuttle feeler and moved by the said filling, 90 95 100 when thus carried forwardly, to rock the locking arm out of engagement with said shoulder upon a forward movement of the cutter member.

5. In a loom, the construction defined in 105 claim 4, together with means for counterbalancing the latch to enable a slight pressure on the bunter arm to rock the latch to unlocking position.

6. In a loom, the construction defined in 110 claim 4, together with a counterbalancing weight adjustable radially of the latch pivot to control the pressure on the bunter arm required to rock the latch to unlocking position.

In testimony whereof, I have signed my name to this specification.

NEM WILLIAM BRANNON.
